UNITED STATES PATENT OFFICE

PAUL SOWADA, OF YONKERS, NEW YORK, ASSIGNOR, BY MESNE ASSIGNMENTS, TO
WELTE-TRIPP ORGAN CORPORATION, A CORPORATION OF DELAWARE

ORGAN-SWELL-CONTROL MECHANISM

Application filed August 28, 1924, Serial No. 734,747. Renewed August 2, 1930.

This invention relates to swell operating mechanisms for organs and its purpose, generally, is to provide a swell operating means operable under control of a record 5 and which will be of generally improved construction by reason of certain novel and advantageous features incorporated therein. Among the particular purposes of the invention is the provision of a swell operating 10 mechanism adapted to open and close swell shutters in succession and at different speeds, under control of a record, to provide crescendo or decrescendo effects at varying speeds as well as sforzando or crash effects.

15 The foregoing objects, including other of a particular nature which will be apparent, to those familiar with the class of invention to which the present one relates, from the drawings and following description and 20 which, therefore, need not be set forth in detail, are well accomplished by the construction illustrated in the accompanying drawing and hereinafter described: it being understood that this particular detail embodiment is merely exemplary and that 25 changes therein may be made without departing from the spirit of the invention defined by the appended claims.

In a general way and as a premise to the 30 description of the particular form of the invention illustrated, I would say that while the particular embodiment illustrated comprises pneumat-o-electric mechanism having means operable under control of a suitably 35 prepared record to successively open and successively close the swell shutters of the organ at different speeds, to produce the varying swell and decrescendo effects called for by an artistic rendition of a musical 40 composition being played, yet successive operation of the shutters in opening and in closing is not wholly essential to the invention, considered in its broadest aspects, while very advantageous and because of its 45 advantages greatly preferred: nor is it wholly essential, although greatly preferred, that the operating mechanism be of a pneumat-o-electric nature. Again, also by way of premise, I would state that in the 50 automatic musical instrument art the present

practice prefers the use of perforated music rolls or note sheets as the records therefor, and with such note sheets it is customary to employ as the tracker member of the mechanism a bar having perforations which correspond with the perforations of the note sheet but novel features embodied in the present mechanism may readily be embodied in a mechanism controlled by a record of different nature from that utilizing the well known and preferred perforated note sheet, with a corresponding change in the tracker member. Therefore, and because this invention is not primarily concerned with any particular style or construction of record or 55 tracker, it should be understood that these words wherever used in the following description and claims unless otherwise qualified, are not intended to be restricted to the well known perforated note sheet and the well known bar with perforations or ducts 60 corresponding to those of the note sheet, but on the contrary are intended to comprehend any suitable form of record and any suitable form of tracker for use with such record. 65

Moreover, in record-controlled musical instruments employing pneumatically operable valves controlled by perforated note sheets, the practice prefers that the pneumatic elements which operate these 70 valves be subjected to pressures which are at and below that of the atmosphere, but it is generally understood that other pressure may be employed provided one is higher than the other. Therefore, while I have 75 illustrated valve operating mechanism of a pneumatic nature wherein the pouches which operate the valves are exposed to a pressure below that of the atmosphere at one side and intermittently to a pressure at 80 that of the atmosphere at the other side, yet it will be understood that this is merely exemplary. Finally, in the operation of 85 these pouches the present practice prefers that they be controlled by suitable pneumatically operated valve mechanisms interposed between them and the tracker of the instrument, because such an arrangement brings about a more responsive operation 90 and the illustrated embodiments shows this 95 100

arrangement of primary and secondary valves but this also is merely exemplary.

In the accompanying drawings, wherein like characters of reference denote corresponding parts,

5 Figure 1 is a diagrammatic view representing the preferred embodiment of a system constructed in accordance with this invention,

10 Figure 2 is a view on an enlarged scale of a portion of the structure shown on Figure 1, diagrammatically shown and with certain of the parts in section,

15 Figure 3 is a cross section on the line 3—3 of Figure 2,

Figure 4 is a cross section on the line 4—4 of Figure 2,

20 Figure 5 is a cross section on the line 5—5 of Figure 2,

25 Figure 6 is an enlarged view of the main block which contains the wind chest for operating the pouch pneumatics which in turn control the valves for operating the switch control power pneumatics,

30 Figure 7 is a view similar to Figure 2 from the opposite side thereof and with the primary pneumatics and tracker omitted.

35 Figure 8 is a plan view of a note sheet having perforations to control the operations of the swell shutters.

In Figure 1, A illustrates a part of a pipe organ provided with swell shutters B, any suitable number of which may be employed.

40 C designates a part of the organ wind chest containing air having a pressure greater than that of the atmosphere. D designates a shutter operating pneumatic here shown as having its movable wall *d* connected to the corresponding shutter by a link *d'*, and adapted by its expansion to close and hold the shutter against the action of a retractile spring *b*, which tends to open the shutter. In practice, there is, preferably, one of these pneumatics D for each shutter and

45 all have their interiors suitably connected by valve controlled passages with the interior of the wind chest C and with the atmosphere at different times. I have illustrated only one of the pneumatics and the means through which its interior has communication at one time with the interior of the wind chest C and at another time with the atmosphere, this being sufficient because the others are merely duplicates thereof.

50 Referring now to the one illustrated, 10 designates a duct which communicates with the interior of the pneumatic and is provided with a port 11 through which it may have communication with the interior of the chest C and also with a port 12 through which it

55 may have communication with the atmosphere. When the port 11 is open and the port 12 is closed, the pressure of the air within the chest C and power pneumatic D, being greater than that of the atmosphere

and tension of the spring *b*, holds the pneumatic in expanded condition and the shutter closed, and when the port 12 is open and the port 11 is closed there will be, as is apparent, a balancing of the pressures of opposite sides of the movable wall *d* of the power pneumatic, whereupon the spring *b* will become operative to open the shutter. The two ports 11 and 12 are controlled from power pneumatics F and G through suitable pneumato-electric means preferably as follows:

70 The stem 14 of the valve 13 is operatively connected with a pouch 15 one side of which is exposed to the pressure in the wind chest C and the other side of which is exposed to the controllable pressure in a chamber 16, said chamber having a duct 17 provided with a port 18 through which it may be vented to the atmosphere under control of a valve 19

75 which is carried by the armature 20 of an electromagnet 21. When the port 18 is closed by the valve 19, the valve 13 will be seated upon the port 12 thereby closing the

80 duct 10 against the atmosphere and opening said duct to the pressure chamber C, there being a suitable port 22, here shown as ar-

85 ranged between the limbs of the magnet 21 in which position it will be opened when the valve 18 is seated over the port 19 and will

85 be closed by said valve when the latter has been moved to open the port 18 by the energizing of the magnet 21. This causes the

90 chamber 16 to be vented to the atmosphere whereupon the pressure in the chest C will

95 expand the pouch 15 and move the valve 13 to close the port 11 and open the port 12 thereby cutting off communication of the in-

100 terior of the pneumatic D with the pressure chamber and opening communication of the interior of said pneumatic with the atmos-

105 phere, and permitting the spring *b* to open the shutter.

110 Each electromagnet is energized and de-

energized to open and close the correspond-

115 ing valve 18 through suitable electrical con-

nections, the connections shown comprising

wires 23 and 24 terminating in spring con-

120 tact 25 and 26.

All of these circuits are controlled by a common switch member which in the form of the invention herein illustrated comprises a body or block E of non-conductive mate-

125 rial, as wood, for example, which slides in guide ways *e* and is provided with a plate E', formed of copper or other suitable con-

130 ductive material and having a diagonal edge *e'*. In the operation of this member the

diagonal edge of the conductive plate en-

contact wires and is used as a ground wire for all of the contact wires.

The movable switch member E is connected by links 27 and 28 with the movable walls of the pneumatics F, and G, in such manner that when the pneumatic F is collapsed said switch member will be operated to close the circuits to the several electromagnets and cause the shutters to be opened, and when the pneumatic G is collapsed said switch member will be operated to again open said circuits and de-energize the magnets, thereby causing the shutters to be closed.

These two pneumatics are operatively related to a valve box H, having, as indicated in Figure 6, a conduit 30 which extends to the interior of the pneumatic F and a like conduit 29 which extends to the interior of the pneumatic G. The valve box is also provided with connected channels 31 and 32 which extend from the conduit 30 to a chamber 33 having an atmospheric port 34 and a suction port 35. A valve preferably the double valve 36 here shown is mounted in the chamber 33 in such relation to the ports that when it is in one of its positions the atmospheric port 34 will be opened and the suction port 35 will be closed and when it is in its other position, said suction port will be opened and said atmospheric port closed. To bring about these movements, its stem 37 is operatively related to a pouch 38, one side of which is exposed to the tension of the air in a suction conduit 39 into which the port 35 opens. The other side of the pouch is exposed to the tension of the air in a chamber 40 which tension is variable, the chamber 40 having a duct 41 through which it may be flushed with air at atmospheric pressure under control of a properly prepared record, as hereinafter set forth.

The conduit 29 is correlated with like channels having atmospheric and suction ports, respectively, controlled by a like valve and pouch, these elements not being shown in detail for the reason that they are duplicates of the corresponding elements described with relation to the conduit 30. The pouch which is correlated with the conduit 29, and which corresponds to the pouch 38, however, is shown in Figure 6 and is marked 38^a and the duct leading to the chamber the flushing of which with atmospheric air expands said pouch 38^a is marked 41^a.

42 and 43 in Figure 6 designate channels leading from the pneumatics F and G, respectively. These channels, respectively, open into members, I, and J, which are of like construction, and contain pneumatically operable means to cause either pneumatic F or G to be vented while the other is being collapsed. Each of said members, in the form of the invention herein shown, has a chamber 44 which is open through a channel

44^a to the atmosphere at all times and is provided with a valve 45 operatively related to a pouch 46 mounted in a chamber 47 and having a spring 48 which tends to expand it and thereby hold the valve 45 upon its seat over the mouth of the corresponding channel 42 or 43. It will be apparent that when the tension of the air in either chamber 47 is reduced sufficiently below that of the atmosphere, the pressure of the latter acting upon the corresponding pouch 46 will move the corresponding valve 45 from its seat and thereby open the way through the corresponding channel 42 or 43 of the corresponding pneumatic with the atmosphere. The operation of the valves 45 to vent the pneumatic G simultaneously with the collapsing of the pneumatic F to open the shutters and to vent the pneumatic F simultaneously with the collapsing of the pneumatic G to close the shutters is accomplished as follows:—

From the chamber 33 which is connected to the conduit 39, channels 50 extend and are connected by a duct 51 with the chamber 47 in the member J, (Figure 4) and like channels having a like cross connection (marked 51^a) to the chamber 47 of the other member I, are provided between the latter chamber 47 and the chamber 33 connected to the conduit 29, the cross connection being indicated in Figures 4 and 6.

It will be understood, now, that the admission of air at atmospheric pressure through the duct 41 will cause the pouch 38 to expand and the switch pneumatic F to collapse, and that this in turn will operate the switch member E to close the circuits successively through the magnets 21, causing the several pneumatics D to collapse and the several shutters B to be opened, and that the operation of the switch member E will be unresisted by the pneumatic G for the reason that the latter will be vented to the atmosphere simultaneously with the opening of the way between the pneumatic F and the suction conduit. Similarly, it will be understood that the admission of air at atmospheric pressure through the duct 41^a will cause the pouch 38^a to expand and the pneumatic G to collapse, and that this in turn will open the circuits successively through the magnets 21, causing the pneumatics D to expand and the shutters B to close, unresisted by the pneumatic F.

The speed at which these operations may be effected may be primarily regulated by properly setting regulating screws 52, with relation to the air passages to the chambers 33, respectively, one of which screws is shown in Figure 4. This, however, is an initial regulation which is usually made at the factory in the case of small organs or during the installation of larger organs.

After this initial regulation has been made

it will still be apparent that the speed of operation should be variable to enable different effects to be produced, as crescendo, sforzando, and the opposites thereof, for example. Therefore, I have provided auxiliary valve mechanisms, which may be operated under control of the record to supplement when desired the operations of the before mentioned valves 36. There is one auxiliary valve mechanism for one set of valves 36 and another auxiliary valve mechanism for the other set of valves 36. As both are identical, a description of one will suffice, and indeed, I have only shown one in detail (Figure 3) although the operating pouches, marked 53 and 54, respectively, are shown in Figure 6 and the ducts through which atmospheric air enters to expand these pouches are shown in Figure 2 and are marked 62 and 62^a in said Figure 3. Upon reference to Figure 3, it will be noted that a chamber 55, having connection with the conduit 30 through ducts 56 and 57 initially controlled by a regulating screw 58, is provided with a port 59 through which it may have communication with the suction conduit. This chamber 55 is also provided with a valve 60 to open and close the port 59 and said valve is in operative relation with the pouch 53, one side of which is exposed to the tension of the air in the suction conduit 39 and the other side of which is exposed to the tension of the air in a chamber 61 having a duct 62 through which it may be flushed with air at atmospheric pressure under control of the record. Thus, when the duct 62 is opened to the atmosphere, the pouch 53 will be expanded at the same time the pouch 38 is expanded and the conduit 30 will be placed in communication with the suction conduit 39 through the port 59 as well as through the port 35, thus resulting in a more rapid collapse of the pneumatic G than takes place when only one of said ports is opened. Similarly when the duct 62^a is opened to the atmosphere, the pouch 54 will be expanded along with the pouch 38^a so that the duct 29 will be placed in communication with the suction conduit 39 through a port like that marked 59 as well as through a port like that marked 35, this as is apparent resulting in a more rapid collapse of the pneumatic G than takes place when a port like 35 is opened alone.

Of course, it will be understood that a gradual crescendo may result from the slower collapse of the pneumatic F and a like decrescendo result from the like collapse of the pneumatic G, and that a rapid crescendo, or sforzando effect, for example, may result from the rapid collapse of said pneumatic F and a like decrescendo or diminuendo result from the rapid collapse of the pneumatic G, all under control of a suitably prepared record.

65 The necessary suction within the appara-

tus is produced through a conduit 63 having suitable connection with an approved pump; as will be well understood.

The ducts 41, 41^a, 62 and 62^a are, of course, opened under control of a properly prepared member constituting a record, or equivalent, as the perforated note sheet L, for example, which travels over a suitable tracker M having special holes 65, 66, 67 and 68. These holes are, respectively, connected, by preference, with primary valve mechanisms, designated N, N', O and O' in Figure 2, by means of ducts 69, 69^a, 70 and 70^a. These valve mechanisms are of identical construction and, therefore, it will suffice to illustrate and describe only one of the same in detail. The one marked N' is shown in section in Figure 2, upon reference to which it will be seen that it comprises a chamber 71; a chamber 72 having a suction port 73 and an atmospheric port 74; a double valve one of whose members, 75, is arranged to open and close the suction port and the other of whose members, 76, is arranged to open and close the atmospheric port; and a pouch 77 which is operatively related to the double valve.

A conduit 78, which in practice is common to all the valve members, is arranged at the side of the several pouches opposite the chambers 71 and is connected around the pouches with said chambers by bleed holes 79. The ducts 69, 69^a, 70 and 70^a, connect the tracker holes 65, 66, 67, and 68 with the chambers 71 in the primary valve mechanisms N, N', O and O', respectively, and the hereinbefore mentioned ducts 41 and 41^a, connect the chambers 72 of the primary valve mechanisms N and N' with the chamber 40 of the main switch operating valve mechanisms, respectively, while the hereinbefore mentioned ducts 62 and 62^a connect the chambers 72 of the primary valve mechanisms O' and O with the chambers 61 of the auxiliary switch operating valve mechanisms.

From the foregoing the operation will be understood to be as follows:—

To produce a crescendo effect, the tracker hole 66 is opened by the registration therewith of a suitably arranged aperture 80 in the note sheet. This admits air at atmospheric pressure to the duct 41 through the action of the primary valve mechanism N' when the latter is employed or directly if 120 said primary valve mechanism be omitted. This atmospheric air flushes the chamber 40 of the main switch operating valve mechanism which controls the deflation of the switch operating pneumatic F and causes 125 movement of the members of the double valve 36 thereof, to the left as viewed in Figure 4, closing communication between atmosphere and the chamber 33 and opening communication between this chamber 33 and 130

the suction conduit 39. Communication is thus established between the chamber 33 through the channels 32 and 31 and conduit 30 to the power pneumatic F (Figures 2 and 6). At the same time, exhaust tension is also created in the channel 50 which, as previously stated is cross connected by a duct 51 to a small chamber 47 (Figure 4) in the member J. Suction being applied in this manner to the chamber 47 of said member J the pouch 46 thereof is collapsed and the corresponding valve 45 withdrawn from its port thereby opening the channel 42 which is in communication with the opposite power pneumatic designated G and venting said pneumatic to the atmosphere, so that the latter pneumatic will offer no resistance to the movement of the switch member E by the collapse of the power pneumatic F which occurs when its interior is placed in communication with the suction conduit 39 by the opening of the suction port 35 and the closing of the atmospheric port 34. The copper plate E' is thus moved under the spring wires 23, 24, the body of the member E sliding in its guideways e (Figure 3). This will cause the diagonal edge e' of the copper plate E' to engage the spring contact wires 25 and 26 progressively beginning at the bottom thereof. As the contact wires successively contact with the copper plate the electro-magnets 21 are energized and the swell shutters successively opened.

I will now describe the operation when it is desired to produce a sforzando effect. At the same time the perforation 82 opens the tracker hole 66, another perforation 83 will open the tracker hole 68. This will result in a flushing of the chambers 61 and 40 through ducts 41 and 62, respectively, thus causing the inflation of the pouches 53 and 38. The operation resulting from the inflation of the pouch 38 is the same as that already described for the crescendo. In addition thereto, by the inflation of the pouch 53 the valve 60 is moved to the left as viewed in Figure 3. This provides an additional connection between the channel 30 and the exhaust tension in chamber 39, through the channels 57 and 56, chamber 55 and port 59, thereby supplementing the first mentioned connection and causing a much more rapid deflation of the pneumatic F with a correspondingly quickened closing of the circuits through all the magnets 21 and opening of the several swell shutters.

As soon as the tracker hole 65 or the tracker hole 66 is closed the corresponding chamber 71 is exhausted through the usual bleed opening 79, the air passing into the conduit 78. This permits the collapse of the pouch 77, the fall of the valves 74 and 75, with a consequent closing of the chamber 72 to atmosphere and its opening to conduit

78, and the exhausting of the chamber 61 and 40 through the respective ducts 41^a and 41. This operation opens the chamber 33 to atmosphere with a consequent movement of the double valve 36 (Figure 4) to the right, a flushing of the ducts 32 and 31 into the channel 30, through the channel 30 to the duct 57, into the duct 56 and the chamber 55, thus permitting the valve 60 to be held in closed position. As soon as the double valve 36 is moved to the right, atmosphere will enter the port 34 and passing by the way of the chamber 33 into the channel 50, the duct 51 and chamber 47, thus permitting the spring 48 to press the valve 45 to the left (Figure 4) and close the duct 42. It will be understood that by means of perforations in the note sheet of different lengths, the crescendo effect may be terminated at any predetermined point between pianissimo and fortissimo if desired.

It will be understood that if a decrescendo effect is desired, the pneumatic G is operated by parts similar to those already described for the operation of the pneumatic F for the crescendo. These parts are under control of perforations registering with the hole 65 of the tracker. In a manner similar to and by parts similar to the auxiliary parts for causing a sforzando effect, the pneumatic G has mechanism and connections which cooperate with the decrescendo mechanism to quickly collapse the pneumatic G, thus quickly closing all of the swell shutters. These auxiliary means are under control of perforations which register with the tracker duct 67.

In Figure 8, I have shown a fragmental view of the tracker and note sheet. As the note sheet travels in the direction of the arrow and the perforation 80 uncovers the tracker hole 66, a crescendo effect is produced by operating the pneumatic F to bring the contact wires slowly and successively in contact with the copper plate E'. When the end of the perforation 80 is reached, the movement of pneumatic F will, of course, stop. When the perforation 81 opens the tracker hole 65, a decrescendo is started by a reverse movement of the pneumatic G and a consequent successive disconnection of the contact wires from the copper plate E'.

As already described the registration of note sheet perforations 82 and 83 simultaneously with their respective ducts 68 and 66, causes the pneumatic F to be quickly collapsed with the result that all of the shutters B are quickly opened, giving a sforzando effect. In the same manner, the simultaneous registration of the perforations 84 and 85 with the tracker holes 65 and 67 will cause the quick collapse of the pneumatic G and result in the quick closing of all the shutters B.

At 86, I have shown two tracker holes il-

lustrative of the note holes; the numerals 87, 88, 89 and 90 designating note perforations in the sheet.

Particular attention is called to the perforation 90 which I have illustrated as an example where it might be desired to produce a crescendo which is slower than the normal crescendo, to be followed by a decrescendo which is slower than the normal decrescendo. 5
10 In order to do this, I place a series of adjacent perforations 91 each of which is of sufficient length to operate the pneumatic F to cause some of the swell shutters to open. Sufficient space 92 is allowed between each 15 two perforations, to permit the pneumatic F to pause in its operation to be later started again in its operation by another perforation. By a manipulation of the lengths of these series of perforations and the spaces 20 therebetween, the desired effects may be obtained. While actually some of these operations in the swell shutters may cease before others are operated, the sequence is so close, 25 in producing any desired effects, that the effect on the ear is a continuous progressive one.

In the same way when the very slow decrescendo is desired, the lengths of the perforations 93 and spaces 94 are adjusted to 30 produce the desired effects.

It will be noted that the operation of the mechanism under control of a record removes the human element of error incident to the use of pedals or the like for controlling the shutters in that there will be no variation in the speed of the shutters, except such variation as is provided for in the record itself. In this exemplification of the invention the regulating means, such as the 35 screws 52 and 58 are provided to bring about, in a most efficient manner, the constancy of speed and a predetermination thereof, it being understood that the constancy here referred to, is that which is present, except 40 when through the record a variation thereof is brought about. If desirable, the screws 52 and 58 may be omitted and the ducts made a proper size to give the proper 45 speed of collapse as will be well understood by those skilled in the art. It is to be understood, however, that a suitable variable 50 regulating means has an important advantage in that careful sizing of the ducts is unnecessary. It will be apparent that the 55 screws 52 and 58 provide a very simple yet effective means of producing the desired results.

Having thus described the invention, 60 what I believe to be new and desire to secure by Letters Patent, and what I therefore claim as my invention is:-

1. In a record controlled organ, swell 65 shutters, a tracker and connections between said tracker and the shutters to cause the

shutters to be operated under control of a record at a predetermined speed.

2. In a record controlled organ, swell shutters, a tracker and connections between said tracker and the swell shutters, including regulating means to predetermine the speed of operation of the shutters. 70

3. In a record controlled organ, swell shutters, a tracker and connections between the shutters and the tracker to operate the 75 shutters at variable speeds under control of a record.

4. In an organ, swell shutters, and operating mechanism for the shutters, comprising tracker controlled means to open the shutters 80 at variable speeds and to close them at variable speeds under control of a record.

5. In an organ, a set of swell shutters, and operating mechanism for the shutters, comprising a tracker and connections between the tracker and the shutters to operate the 85 shutters of the set successively under control of a record.

6. In an organ, a set of swell shutters, and operating mechanism for the shutters, comprising tracker controlled means to operate the shutters of the set successively and at 90 variable speeds, under control of a record.

7. In an organ, swell shutters, and operating mechanism for the shutters, comprising 95 tracker controlled means to operate the shutters and at different selected speeds and to terminate their operation at different selected places, under control of a record.

8. In an organ, swell shutters, and operating mechanism for the shutters, comprising tracker controlled means to operate the shutters successively and at different selected speeds and to terminate their operation 100 at different selected places, under control of a record. 105

9. In a record controlled organ, a tracker, a set of swell shutters, and an operating mechanism for the shutters including separate connections to the shutters, respectively, 110 together with a slidable controlling member for the connections, and an operating pneumatic for said member provided with a connection to the tracker.

10. In a record controlled organ, a set 115 of swell shutters and operating mechanism therefor, including a slidable control member, a separate connection to each shutter, in operative relation to the control member to be successively and individually controlled 120 thereby, and means under control of a record and operative to impart continuous sliding movement to the control member to thereby cause individual and successive operations of the shutters. 125

11. In a record controlled organ, a set of swell shutters and operating mechanism therefor including record controlled pneumatics common to the shutters and separate pneumato-electric connections between said 130

pneumatics and the respective shutters of the set, to operate individually and successively under control of a record.

12. In a record controlled organ, a set of swell shutters, a pair of power pneumatics, connections between the same and the shutters, a record controlled means operable with relation to one of the power pneumatics to open the shutters of the set successively and 10 with relation to the other power pneumatic to close the shutters of the set successively.

13. In a record controlled organ, a set of swell shutters, a pair of power members, connections between the power members and the 15 swell shutters including separate members connected to the shutters, respectively, and operative successively to open the swell shutters successively under control of one power member and close them under control of the 20 other power member, and tracker controlled connections, to control said power members under control of a record.

14. In a record controlled organ, a set of swell shutters, a pair of power members, 25 connections between the power members and the swell shutters to open the swell shutters successively under control of one power member and close them successively under control of the other power member, and 30 tracker controlled connections, to control said power members under control of a record; said connections including means to cause the operation of neither power member to be resisted by the other.

35 15. In a record controlled organ, a set of swell shutters, a pair of power members, connections between the power members and the swell shutters to open the respective swell shutters successively under control of one 40 power member and close them under control of the other power member, and tracker controlled connections, to control said power members under control of a record; the connections between the power members and the 45 shutters and also the tracker controlled connections to the power members including means correlated to cause the operation of neither power member to be resisted by the other.

50 16. In a record controlled organ, a set of swell shutters, a pair of power members, connections between the power members and the swell shutters to open the swell shutters successively under control of one power member and close them successively under control of the other power member, and tracker controlled connections, to control said power members under control of a record; the connections between the power 55 members and the shutters including a separate connection to each shutter and a control member common to said separate connections and also common to both power members and the tracker controlled connections to the 60 power members including means to cause the 65

operation of neither power member with relation to said controlled member to be resisted by the other.

17. In a record controlled organ, a set of swell shutters, a pair of power members, 70 connections between the power members and the swell shutters to open the swell shutters of the set successively under control of one power member and close them successively under control of the other power member, including a member common to both power members, and tracker controlled connections to the power members including means to render either of the power members operative and simultaneously therewith the other power member inoperative with relation to the common member, under control of a record.

18. In a record controlled organ, a set of swell shutters and record controlled mechanism, including a pair of members having connection with the shutters and operable respectively to open and close the same successively, and record controlled connections to said members to cause them to be moved 80 simultaneously and in corresponding directions to cause neither to prevent the operation of the other.

19. In a record controlled organ, swell shutters, power pneumatics, connections between the power pneumatics and the swell shutters to cause the latter to be opened when one power pneumatic is operated and to be closed when the other power pneumatic is 90 operated and tracker controlled connections to the power pneumatic including means to bring about an equalization of pressure on both sides of either power pneumatic simultaneously with a variation in the pressures on opposite sides of the other power pneumatic.

20. In a record controlled organ, swell shutters, power pneumatics, connections between the power pneumatics and the swell shutters to cause the latter to be opened when one power pneumatic is operated and to be closed when the other power pneumatic is operated including a control member having connection with both power pneumatics and tracker controlled connections to the power pneumatics including means to bring about an equalization of pressure on both sides of either power pneumatic simultaneously with a variation in the pressure on opposite sides of the other power pneumatic.

115 21. In a record controlled organ, swell shutters, power pneumatics, connections between the power pneumatics and the swell shutters to cause the latter to be opened when one power pneumatic is operated and to be closed when the other power pneumatic is operated and tracker controlled connections to the power pneumatics, including connections between the pneumatics, controlled from a common duct correlated to 120 125 130

- bring about an equalization of pressure on both sides of one power pneumatic simultaneously with a variation in the pressures on opposite sides of the other power pneumatic.
22. In a record controlled organ, swell shutters, power pneumatics, connections between the power pneumatics and the swell shutters to cause the latter to be opened when one power pneumatic is operated and to be closed when the other power pneumatic is operated, including a control member having connection with both power pneumatics and moved thereby on a straight line and tracker controlled connections to said power pneumatics to operate the same under control of a record.
23. In a record controlled organ, swell shutters, power pneumatics, connections between the power pneumatics and the swell shutters to cause the latter to be opened when one power pneumatic is operated, and to be closed when the other power pneumatic is operated, including a control member having connection with both power pneumatics and tracker controlled connections to the power pneumatics including means to bring about an equalization of pressure on both sides of either power pneumatic simultaneously with a variation in the pressure on opposite sides of the other power pneumatic.
24. In a record controlled organ, swell shutters, a pair of power pneumatics, connections between the same and the shutters, record controlled means operable with relation to the power pneumatics to open and close the shutters, respectively, and in each of said operations to cause the pneumatics to move simultaneously and in the same direction with relation to the shutters so that the operation of neither pneumatic is prevented by the other.
25. In a record controlled organ, swell shutters, a pair of power pneumatics, connections between the same and the shutters, and record controlled means operable with relation to the power pneumatics to open and close the shutters, respectively, and in each of said operations to cause the pneumatics to move simultaneously and in the same direction with relation to the shutters, under control of a common duct.
26. In a record controlled organ, swell shutters and operating mechanism therefor, including electrical circuits and means including a slidable contact member under control of a record to open the circuits individually and successively and close the circuits individually and successively.
27. In a record controlled organ, swell shutters and operating mechanism therefor, including electrical circuits and means including a slidable contact member under control of a record to open the circuits and to close them individually and successively.
28. In a record controlled organ, swell shutters and operating mechanism therefor, including electrical circuits and means under control of a record to open and close the circuits at different speeds.
29. In a record controlled organ, swell shutters and operating mechanism therefor, including electrical circuits and means under control of a record to open the circuit successively and close them successively, at different speeds.
30. In a record controlled organ, swell shutters and operating mechanism therefor, including electrical circuits and means under control of a record and operable with relation to said circuits to open and close the shutters to a predetermined extent.
31. In a record controlled organ, swell shutters and operating mechanism therefor, including electrical circuits and means under control of a record and operable with relation to said circuits to open and close the shutters to a predetermined extent at different speeds.
32. In a record controlled organ, swell shutters and operating mechanism therefor, including electrical circuits for the respective shutters, operating means having connections with the shutters and respectively controlled by the circuits, a switch member common to all the circuits, and means under control of a record to operate the switch member to open and close the circuits.
33. In a record controlled organ, swell shutters and operating mechanism therefor, including electrical circuits, operating means having connection with the shutters and respectively controlled by the circuits, a switch member common to all the circuits and arranged with relation thereto to open them successively and to close them successively, and means under control of a record to operate the switch member.
34. In a record controlled organ, swell shutters and operating mechanism therefor, including electrical circuits, operating means connected to the shutters and respectively controlled by the circuits, a switch member common to all the circuits and means under control of a record to operate the switch member at different speeds to open and close the shutters at correspondingly different speeds.
35. In a record controlled organ, swell shutters and operating mechanism therefor, including electrical circuits, operating means connected to the shutters and respectively controlled by the circuits, a switch member common to all the circuits and means under control of a record to operate the switch member to open or close all or less than all of the circuits to correspondingly open or close all or less than all of the shutters, as predetermined.
36. In a record controlled organ, swell

- shutters and operating mechanism therefor, including electrical circuits, means respectively connected to the shutters to open and close the same under control of the circuits, a switch member movable in a straight line and common to all the circuits, said circuits having contacts and said contacts and switch member being relatively arranged to cause the circuits to be closed successively and opened successively by the straight line movements of the switch in opposite directions, respectively, and record controlled means to operate the switch member in opposite directions.
37. In a record controlled organ, swell shutters and operating mechanism therefor, including electrical circuits, operating means connected to the shutters and respectively controlled by the circuits, a switch member common to all the circuits, and record controlled pneumatic means positively connected to the switch member and operating the same to open and close the shutters under control of a record.
38. In a record controlled organ, swell shutters and operating mechanism therefor, including electrical circuits, operating means connected to the shutters and respectively controlled by the circuits, a switch member common to all the circuits and arranged with relation thereto to open them successively and close them successively, and record controlled pneumatic means positively connected to the switch member and operating the same.
39. In a record controlled organ, swell shutters and operating means therefor, including electrical circuits, means respectively connected to the shutters to open and close the same under control of the circuits, a switch member movable in a straight line, said circuits having contacts and said contacts and switch member being relatively arranged to cause the circuits to be closed successively and opened successively by the straight line movement of the switch member in opposite directions, respectively, and record controlled pneumatic means positively connected to the switch member to operate the same.
40. In a record controlled organ, swell shutters and operating mechanism therefor, including electrical circuits, operating means connected to the shutters and respectively controlled by the circuits, a switch member common to all the circuits and record controlled pneumatics positively connected to the switch member and operable thereon the one to impart continuous movement thereto to open the circuits and the other to close the circuits, to thereby impart continuous movement to the switch member to close and open the shutters.
41. In a record controlled organ, swell shutters and operating mechanism therefor,
- including electrical circuits, operating means connected to the shutters and respectively controlled by the circuits, a switch member common to all the circuits and record controlled pneumatics connected to the switch member and operable thereon the one to open the circuits and the other to close the circuits and means under

control of a record to operate with relation to the pneumatics to move the switch member at different speeds in either direction and to terminate the movements thereof at different predetermined places within the limits of its extreme movements.

46. In a record controlled organ, swell shutters, pneumatic power means, means controlled by the power means to open and close the shutters, and means, including a plurality of air openings having connection with the pneumatic power means and elements under control of a record to severally control said openings, to operate the power means at different predetermined speeds to thereby open or close the shutters at correspondingly different speeds.

47. In a record controlled organ, swell shutters, a power pneumatic having connection with the shutters to open the same, a second power pneumatic having connection with the shutters to close the same, and record controlled pneumatic connections to the power pneumatics, respectively, each having a plurality of air openings having connection with the corresponding power pneumatic, and means under control of a record to severally control the air openings in each connection to operate the corresponding power pneumatic at different predetermined speeds, for the purposes set forth.

48. In a record controlled organ, swell shutters, pneumatic power means, means controlled by the power means to operate the shutters, and means under control of a record to control the pneumatic power means correlated therewith to stop the operation of the power means at different predetermined positions and to maintain it in its stopped position.

49. In a record controlled organ, swell shutters, a power pneumatic having connection with the shutters to open the same, a second power pneumatic having connection with the shutters to close the same, and means under control of a record to control the power pneumatics, said means being correlated with the power pneumatics to stop the operation of either at different predetermined positions and to maintain the same in its stopped position.

50. In a record controlled organ, swell shutters, a pair of power pneumatics, means controlled by one power pneumatic to open the shutters and by the other power pneumatic to close the shutters, and a single means under control of a record to render one power pneumatic operative and at the same time cause the other to be opened to atmosphere.

51. In a record controlled organ, swell shutters, a pair of power pneumatics, means controlled by one power pneumatic to open the shutters and by other power pneumatic to close the shutters, and pneumatic connec-

tions to the power pneumatics, respectively, having a controlling means under control of a record for each power pneumatic to cause the same to move and at the same time to render the opposite power pneumatic inert.

52. In a record controlled organ, swell shutters, power pneumatics, connections for controlling the operation of the shutters from the operation of the power pneumatics, a tracker, a control pneumatic, a connection from the tracker to the control pneumatic, a valve in position to be operated by the control pneumatic, a port under control of the valve leading to one of the pneumatics, a port leading to the other pneumatic and connected to the pressure outside the pneumatic, a second valve for controlling the last named port, a pneumatic for operating the valve and a connection to the last named pneumatic under control of the first named valve.

53. In a record controlled organ, swell shutters, power pneumatics, connections for controlling the operation of the shutters from the operation of the power pneumatics, a tracker, a control pneumatic, a connection from the tracker to the control pneumatic, a valve in position to be operated by the control pneumatic, a port under control of the valve leading to one of the pneumatics, a second control pneumatic, a tracker connection to the second control pneumatic, a valve under control of the second control pneumatic and in position to be operated thereby, a port under control of the second control valve leading to the same pneumatic as the first named port, a port leading to the other pneumatic and connected to the pressure outside the pneumatic, a port controlling valve for controlling the last named port, a pneumatic for operating the last named valve and a connection to the last named pneumatic under control of the first named valve.

54. In a record controlled organ, a set or group of swell shutters, means under control of the record to open or close the shutters successively and at a selective slow or faster speed, and a note record having two lines of perforations to control the operation of a swell mechanism, one of the lines of perforations to control operation at a slow speed and both together to control operation at a faster speed.

55. In a record controlled organ, a set or group of swell shutters, means under control of the record to open or close the shutters successively and at a selective slow or faster speed, and a note record having four lines of perforations to control the operation of a swell mechanism, two of the lines of perforations to control, respectively, the slow opening and slow closing of the swell mechanism and the other two, each with the corresponding one of the first two, control-

ling respectively the fast opening and fast closing of the swell mechanism.

56. In a record controlled organ, the combination of a series of successively operable swell shutters, a tracker having a hole, means movable with relation to said tracker and having perforations of relatively different length to register with said hole, and mechanism connected to the shutters and responsive to air tensions induced by the opening of the tracker hole to cause one or more of the shutters to be operated, the number of shutters operated being in accord with the length of the perforation in registration with the tracker hole.

15 57. In a record controlled organ, the combination of a series of successively operable swell shutters, a tracker having a plurality of holes, means movable with relation to said tracker to control the opening and closing of said tracker holes, and means connected to the shutters and responsive to air tensions induced by the opening of said tracker holes to cause the operation of the swell shutters at variable speeds according to whether one of the tracker holes is opened alone or both are opened together.

58. In a record controlled organ, the combination of a series of successively operable swell shutters, a tracker having one pair of holes for the opening of the shutters and another pair of holes for the closing of the shutters, means movable relatively to the tracker and operative to open and close one hole of either pair or both holes of either pair, as predetermined, and means connected to the shutters and responsive to the air tensions induced by the opening of said tracker holes to cause the shutters to be opened at one speed when one and at a different speed when both, of the corresponding tracker holes, are opened and to cause the shutters to be closed at one or another speed when one or both corresponding tracker holes are opened, respectively.

45 59. In a record controlled organ the combination of swell shutters, means for actuating said shutters successively and selectively at different speeds, and means for controlling operation of said shutter actuating means including a record having a plurality of lines of perforations so related to said actuating means as to operate the latter at one speed when one line of perforations is rendered effective and at a different speed when more than one line is rendered effective.

60 60. In a record controlled organ the combination of swell shutters, means for actuating said shutters successively and selectively as different speeds, and means for controlling operation of said shutter actuating means including a record having a plurality of lines of perforations so related to said actuating means as to operate the latter at one speed

when one line of perforations is rendered effective and at a different speed when another line is rendered effective.

In testimony whereof I affix my signature.

CERTIFICATE OF CORRECTION.

Patent No. 1,796,222.

Granted March 10, 1931, to

PAUL SOWADA.

It is hereby certified that error appears in the printed specification of the above numbered patent requiring correction as follows: Page 9, lines 61, 62 and 63, claim 40, strike out the words "impart continuous movement to the switch member to" and insert the same to follow the word "to" first occurrence, in line 61, of same claim; and that the said Letters Patent should be read with this correction therein that the same may conform to the record of the case in the Patent Office.

Signed and sealed this 5th day of May, A. D. 1931.

(Seal)

**M. J. Moore,
Acting Commissioner of Patents.**
